[57] CLAIM

The ornamental design for a molded insulating base for an electrical apparatus, substantially as shown and described.

DESCRIPTION

FIG. 1 is a side elevational view of a molded insulating base for electrical apparatus according to this invention; FIG. 2 is a top view of the base of FIG. 1; FIG. 3 is a bottom view of the base of FIG. 1; FIG. 4 is a side elevational view of the base of FIG. 1 inverted about its horizontal axis; FIG. 5 is a front elevational view of the base of FIG. 1; FIG. 6 is a back elevational view of the base of FIG. 1.
